UNITED STATES PATENT OFFICE.

JOHN L. DOLAN, OF ETNA, PENNSYLVANIA.

CAR-REPLACER.

1,172,014.

Specification of Letters Patent. Patented Feb. 15, 1916.

Application filed March 23, 1915. Serial No. 16,368.

To all whom it may concern:

Be it known that I, JOHN L. DOLAN, a citizen of the United States, residing at Etna, Allegheny county, Pennsylvania, have invented a new and useful Improvement in Car-Replacers, of which the following is a full, clear, and exact description, reference being had to the accompanying drawings, forming part of this specification, in which—

Figure 1 is a plan view of a portion of railway and a car replacer of one type in position for replacing the car on the two rails. Fig. 2 is an end view with the rails in section. Fig. 3 is a plan view of a rail replacer. Fig. 4 is a sectional view on the line IV—IV of Fig. 3. Fig. 5 is a side elevation of a replacer from the rail side; and Fig. 6 is an inverted plan view.

My invention relates to an improvement in portable car replacers, which can readily be placed in position with relation to the rail, and readily removed after the car has been replaced.

Another object of my invention is to provide a replacer in which the means for holding it against longitudinal and lateral movement are carried by the replacer itself, thus obviating the use of loose or separate fastenings, such as bolts and spikes which are likely to work loose or become lost.

The precise nature of my invention will be best understood by reference to the accompanying drawings, which will now be described, it being premised, however, that various changes may be made in the details of construction, without departing from the spirit and scope of my invention as defined in the appended claims.

Referring to the accompanying drawings the reference character 2 designates the rail supporting ties, 3 the rail secured thereto by means of the usual spikes 4.

5 is the replacer, there being two shown in Fig. 1 which are of similar construction, and each of which is adapted to replace the wheels on one side of the car on the rail adjacent thereto.

The upper surface of the replacer is inclined upwardly from the ends toward the center thereof, and slopes downwardly from the outer edge toward the rail side 6, as indicated in Figs. 2, 4 and 5. The central portion of the top surface is provided with a depression 7 which slopes downwardly toward the rail side, and is arranged to pre-

vent the wheels from passing the center of the replacer. The replacer is of hollow form, the outer edge 5^a extending from the top of the replacer to the bottom thereof and forming a strengthening web for the structure. The lower face of this side is approximately in the same plane as the top surface of the ties, the replacer being of sufficient length to span adjacent ties. The rail side 6 of the replacer is cut away as indicated at 8 to span the securing spikes for the rails.

9 are transverse strengthening webs extending from side to side of the structure 70 and from the top to the bottom thereof. Extending laterally from the rail side 6 of the replacer and from approximately the center portion thereof, is a retaining member 10, the outer end of which is provided 75 with a hook 11 adapted to extend over the side of the foot of the rail farthest from the rail side of the replacer.

12, 12 are projections on the sides of the replacer which extend below the top surface 80 of the ties 2, each of which is arranged to engage the inner face of one of the ties to prevent longitudinal movement of the replacer. The distance between the outer edge of each of these projections and 85 the end of the replacer is less than the width of the tie, so that the wheels of the car to be replaced will first roll up on the tie and then on the inclined surface of the replacer.

When placing the device in position with 90 relation to a rail, the projection 10 is passed under the rail a sufficient distance to pass the hook 11 beyond the opposite edge of the foot of the rail. The replacer is then dropped onto the ties and moved back to 95 draw the hook over the foot of the rail. It is then moved in a longitudinal direction over the ties, in the direction of the movement of the car to be replaced, to bring one of the projections 12 against the tie. The 100 car is then moved toward the replacer, so that the wheels will roll up its inclined top surface. The wheel flanges on the left-hand side of the car will bear on the incline, while the outer portion of the tread of the 105 wheel on the right-hand side of the car will rest on the incline. The longitudinal movement of the car will raise the wheels, while the lateral slope will slide the wheels toward the rails. As soon as the wheels are 110 elevated sufficiently the lateral slope will cause them to move toward the rails.

The advantages of my invention result from the provision of a replacer which is supported on the ties and is placed adjacent to the rail, and which is provided with its own securing devices of a character to prevent lateral and longitudinal movement of the replacer, the use of auxiliary securing devices being dispensed with.

I claim:

- 10 1. A portable car replacer adapted to be placed at one side of a rail, the upper surface of the replacer sloping downwardly from the center toward each end, and a securing member rigidly connected thereto extending laterally from the lower portion at the rail side thereof and adapted to extend below the foot of the rail between the ties, said member having a projection adapted to engage that side of the foot of the rail farthest from the car replacer, a hook on the end of the projection, said hook being spaced a sufficient distance from the side of the replacer to permit the foot of a rail to pass between the end of the hook and the replacer; substantially as described.
- 15 2. A portable car replacer adapted to be placed at one side of a rail, the upper surface of the replacer sloping downwardly from the center toward each end, a securing member rigidly connected thereto extending laterally from the lower portion at the rail side thereof and adapted to extend below the foot of the rail between the ties, said member having a projection adapted to engage
- 20 30 35 40 45 50 the side of the foot of the rail farthest from the car replacer, a hook on the end of the projection, said hook being spaced a sufficient distance from the side of the replacer to permit the foot of a rail to pass between the end of the hook and the replacer, and downwardly extending projections adapted to engage the sides of the ties; substantially as described.
3. A portable car replacer adapted to be placed on one side of a rail, the upper surface of the replacer sloping downward from the center toward each end and from the outer side toward the rail side, there being a laterally sloping recess in the upper surface of the replacer at the center thereof, said recess sloping from the outer side to-

ward the rail side, and a securing member formed integrally therewith extending laterally from the lower portion at the rail side thereof, said securing member being arranged to extend below the foot of the rail between the ties and engage the side of the foot farthest from the replacer; substantially as described.

4. A portable car replacer adapted to rest upon two adjacent rail supporting ties at the side of the rail, said replacer having an inclined upper surface, projections extending downwardly from the replacer, each of said projections being arranged to engage the inner face of one of said ties, and a securing member formed integrally therewith and extending from the replacer under the rail between the ties and arranged to engage the side of the foot of the rail farthest from the replacer to prevent lateral movement of the replacer, a hook on the end of the projection, said hook being spaced a sufficient distance from the side of the replacer to permit the foot of a rail to pass between the end of the hook and the replacer, said projection being spaced a sufficient distance from the side of the replacer to permit the foot of the rail to pass between the projection and the replacer; substantially as described.

5. A portable car replacer adapted to rest upon two adjacent rail supporting ties at the side of the rail, said replacer having an inclined upper surface, projections extending downwardly from the replacer, each of said projections being arranged to engage the inner face of one of said ties, the length of the replacer from the projections to the ends thereof being less than the width of a tie, a securing member formed integrally therewith extending from the center of the replacer under the rail, and a hook on the end of said member adapted to engage the side of the foot of the rail farthest from the replacer; substantially as described.

In testimony whereof, I have hereunto set my hand.

JOHN L. DOLAN.
